UNITED STATES PATENT OFFICE.

JAMES P. WALLACE, OF BELLEFONTAINE, OHIO.

PLASTER-OF-PARIS SPLINT.

SPECIFICATION forming part of Letters Patent No. 316,421, dated April 21, 1885.

Application filed January 2, 1885. (Model.)

To all whom it may concern:

Be it known that I, JAMES P. WALLACE, a citizen of the United States, and resident of Bellefontaine, in the county of Logan and State 5 of Ohio, have invented a new and useful Improvement in Plaster-of-Paris Dressings, of which the following is a specification.

My invention is an improvement in plaster-of-paris dressings for treatment of fractures, 10 spinal curvatures, &c., in surgery; and it consists, essentially, in making the splint complete before applying it to the limb by measuring the limb and cutting the material to correspond by means of patterns or otherwise, in 15 preparing the splints after the measurements are taken, so as to form a self-supporting spring-splint, and in the process of retaining the limb in extension or in the position desired.

20 My patterns are made to correspond with the different parts to be treated—viz., the leg, thigh, forearm, upper arm, or whole arm, &c.—and are made of heavy card-board bound with a metallic edge, or of other suitable material; 25 but the measurements may be taken in any manner and transferred to the cloth.

Figure 1 is a view of my dressing or splint applied to the lower part of the leg, showing a slight line left open for inspection along the 30 anterior median line, also the support for the foot, and the re-enforce at the ankle. Fig. 2 is a view of my dressing that has been set on a limb and removed, preserving its shape intact and ready to be sprung open and read- 35 justed to the limb. Fig. 3 is a view of a splint molded to the arm and removed.

A represents the line for measurement at the ball of the foot in making a splint for the lower leg; B, measurement at the instep; C, 40 heel-measurement; D, ankle-measurement; E, midway between the ankle and calf; F, calf-measurement; G, measurement of point below the knee, or the top of the lower leg pattern.

H represents my lower leg pattern placed on 45 the cloth or material the splint is to be cut from; K, a series of holes on the lines K', one-fourth of an inch apart, crosswise of the pattern, through which the measurements of the leg are transferred to the cloth; L, a scale on 50 the straight edge of the pattern; M, scales on either end of the pattern, made on plan of one-half inch to the inch, to transfer circumfer-

ence-measure of limb by; N, dotted lines showing part to be folded over when the foot or shoe of the splint is bent up, forming a re-enforce for the ankle; O, the anterior surface of the leg, showing above my splint or bandage.

The object is to prepare an effective dressing with as little handling of the limb as possible, and one that will accommodate itself to 60 the swelling or shrinkage of the limb, and always be open for inspection. The measurements can be taken from the corresponding sound limb in case of fractures, and the fractured member not bothered until the completed splint is applied.

The mode of preparing and applying my splint is as follows: The measurement of the limb is taken at the different parts, including the measurement of the distal extremity and 70 the intermediate points, down to the smallest point of circumference, and marked upon the goods. The shape of the limb is thus transferred to the goods and then cut out.

By doubling the cloth before cutting I thus get 75 two pieces—duplicates of each other—which form the wrapper and lining for my splint. One of these pieces I now lay upon a table or other smooth surface, mix my plaster-of-paris to the consistency of cream, and with a spoon 80 hastily spread it over the whole surface of the cloth, excepting about one-half inch along each edge. I then lay my duplicate piece of cloth on the plaster and unite the whole by slight pressure of the hands and apply it to 85 the limb, (an assistant holding the same in extension at the time,) fitting it snugly to all irregularities and inequalities by pressure of the hands. The last or top layer of cloth 90 that was put on is applied next to the limb. The plaster setting before it has passed through, this layer forms a desirable lining, and is the only lining needed. I then wrap the entire splint with the ordinary roller-bandage, and leave it thus until the plaster 95 sets. The moisture in the plaster in the meantime has shrunken the cloth until an open line has been left for inspection down the entire anterior surface of the limb. The plaster, not having been spread to the edge of the 100 pieces, leaves a soft edge to the splint, free from crumbling or chafing. After the plaster has fully set, the roller-bandage may be removed and a few strips substituted, leaving a

space exposed along the anterior line of the limb for inspection, the splint forming a uniform and equable support at all points.

By spreading the plaster uniformly throughout the dressing I secure a firm support for the posterior surface of the limb, and create a snug-fitting spring-splint that yields sufficiently to accommodate itself to the swelling incident to a fractured bone, but which also accommodates itself to the shrinkage of the limb after the swelling departs, and the shrinkage that always attends the disuse of a limb.

One splint will usually last throughout the treatment of a fracture, can be sprung open 15 at any time to remove, and can be readily re-adjusted. It is customary in other modes to make a temporary splint, and replace it after several days with a permanent splint; but with my self-adjusting spring-splint the dressing 20 or splint applied immediately after reduction of the fracture becomes the permanent splint.

I am aware that plaster-of-paris dressings have been used before in the treatment of fractures, and I wish to disclaim the idea, broadly, of using a plaster-of-paris dressing, and only to claim a process that will worry the injured limb the least, that is self-supporting, that fits the limb snugly, having no 25 rough edges, that leaves a line open for inspection, that can be sprung open to remove or replace, and that, being a spring bandage or splint, yields to the swelling of the limb or fits snugly, notwithstanding shrinkage, and 30 wherein the plaster is spread before being applied to the limb. Heretofore plaster-of-paris dressings have been such as the common roller-bandage or the Bavarian dressing. In 35 both of these methods the fitting and prepara-

tion must all be done on the leg. It is impossible to get a perfectly-even distribution of the plaster, the limb does not have that effective support at all points that it has in my mode, and the muss and litter attending the Bavarian are very encumbering and annoying. 40 45

I find it very desirable to dampen my goods before applying the plaster, as it adheres more easily and the goods shrink more evenly.

My process and splint are applicable to the treatment of deformities (club-feet, &c.) as 50 well as to the treatment of fractures cited.

What I claim is—

1. A supporting spring bandage or splint encircling more than three-fourths of the limb, and composed of two outside pieces of textile 55 fabric united by plaster-of-paris, the whole splint being made before being applied to the leg or other part, and forming, when set, a perfectly-fitting spring-splint, open along its anterior median line for inspection, and capable of being removed and replaced at will, 60 substantially as shown and described.

2. The process of constructing a spring plaster-of-paris splint for treatment of fractures, &c., wherein the preparatory steps are all 65 made without disturbing the limb or part treated, the process consisting of the measurement of the limb, the cutting of two pieces of textile fabric to the proper shape by means of an adjustable pattern having the contour 70 of the limb, and the uniting the pieces by means of a solution of plaster-of-paris, and then molding the same to the limb, substantially as described and set forth.

JAMES P. WALLACE.
